UNITED STATES PATENT OFFICE.

EUGENE F. MITCHELL, OF SPOKANE, WASHINGTON.

LUMBER-MARKER.

1,262,826.

Specification of Letters Patent. Patented Apr. 16, 1918.

Application filed March 14, 1917. Serial No. 154,787.

To all whom it may concern:

Be it known that I, EUGENE F. MITCHELL, a citizen of the United States, residing at Spokane, in the county of Spokane and 5 State of Washington, have invented certain new and useful Improvements in Lumber-Markers, of which the following is a specification.

My invention relates to improvements in 10 lumber-markers, and the principal object thereof is the provision of a novel and efficient device of this character which will operate automatically to print, stamp, impress or emboss upon the ends of boards or 15 other lumber, letters, numerals, trademarks, symbols, etc., or other descriptive matter.

A further object resides in providing a 20 device of the class indicated which is of such extremely simple, cheap, and compact construction as to render it highly practicable and especially desirable in fulfilling its intended office.

Generally speaking, the device comprises 25 automatic mechanical means for stamping the desired legend upon the ends of boards after milling, planing, and so forth, as they pass from the machines or are being conveyed to points for storage or shipment. This means includes a pivotally mounted 30 lever, a marking die carried thereby, a latch device adapted to retain the lever in raised, inoperative position, a setting and tripping member for the lever, and a positive spring tensioning means adapted to impart the 35 necessary impact of the die upon the lumber and to retract the tripping member.

In the drawings accompanying this application,

Figure 1 is a side elevation showing the 40 mechanism, the casing being in cross-section and mounted in position, the elements of the apparatus being in the relative positions they assume at the instant of release of the die-lever.

Fig. 2 is a similar view showing the positions of the parts of the action during the progress of a board after the same has been stamped or marked.

Fig. 3 is a transverse section through the 50 casing on the section lines of Fig. 1, showing the mechanism as viewed from the left of the latter figure.

Fig. 4 is an enlarged side view of the marking-lever.

Fig. 5 is an enlarged front view of the same,

Fig. 6 is a greatly enlarged view, partly in section, showing the construction of the marking-die, the view being taken on the section line of Fig. 4. 60

Fig. 7 indicates the end of a board with the desired mark stamped thereon.

Referring more specifically to the drawings in which like characters of reference are used to indicate like parts in the several views, the numeral 1 designates a housing or casing in which the mechanism comprising my device is inclosed. An actuating-lever 2 is pivotally supported by pins 3 which extend through the side walls of 70 the casing and are secured in place by nuts 4. This actuating-lever is formed with a pair of L-shaped arms 5 and 6 integral with the pivotal axle portion 7 of the lever, the arm 6 being preferably of web-like design, 75 and both mounting at their free ends a lumber engaging roller 8.

A bifurcated die-lever 9 is pivotally supported for swinging movement by the actuating-lever 2 upon a shaft 10 and to 80 the side of the arm 6 in a position to wipe past the arm into the positions indicated in Figs. 1 and 2.

A latch-member 11 is pivotally mounted at 12 in the short arm 2' of the lever 2, and 85 a convolute compression spring 13 has its opposite ends secured to the lever arm 2' and to said latch member 11; being wound about the pivot portion 12.

The die-lever 9 has pivotally mounted at 14 at its outer end a balanced die 15 which is connected by a spring 16 with a pin 17 near the upper end of said lever. The lever is provided with an extension 18 formed with a groove 19, a catch-recess or notch 20, 95 and a slightly concave roller engaging surface 21. An additional spring latch or detent member 22 is pivotally supported by one of the side walls of the casing and is adapted to engage the free end 23 of the 100 latch-member 11. An elongated flat spring 24 is secured in position within the casing by a pin 25, the upper end of the spring being connected by a rod 26 to the extension 18 at a point 27. The spring is also 105 provided with an upset end 28 which is adapted to be engaged by the die-lever 9 to provide a yielding stop to limit the movement of the lever in that direction.

In operation, the roller 8 is adapted to be 110 engaged successively, by the boards from a planing, shaping, or other machine as they

pass endwise therefrom. Such a machine is indicated at 29. In Fig. 2 is illustrated the relative positions of the working parts while a board 30 is traveling below the 5 marker. At such time the actuating-lever 2 is pushed forwardly or to the left. During the forward movement of said actuating-lever the concave surface 21 of the die-lever 9 will be brought into engagement with a 10 fixed roller 31 projecting inwardly from one side of the casing, and in consequence will be tilted from a depending position until it takes the position shown. Simultaneously with said forward movement of lever 2 the 15 spring connected latch-member 11 will be drawn by the lever until its catch or notch 32 locks with the latch recess 20 of die-arm 9, further movement of the latch-member being limited by the fixed roller 31. 20 When the board drops from the machine 29 and thereby out of engagement with roller 8, the actuating-lever 2 will be retracted into the position shown in Fig. 1 by the action of the spring 24, and the latch-member forced into engagement with the spring controlled detent 22 where it will be retained pending the succeeding forward movement of the actuating-lever.

In Fig. 1 a board 33 is shown in actuating relation to roller 8 immediately after the latter has been slightly advanced by the board and thereby effected the release of the die-lever which is under strong tension of the spring 24 and is illustrated as positioned 30 at the moment of its release by the latch-recess 32 from which position it swings downwardly upon its pivot and the die is brought into contact with the end of the advancing board.

40 A most important feature of my invention consists of the particular means for mounting the die 15. In Fig. 6, which is an enlarged detail view, a block 34 is shown pivotally supported between the side arms 45 of the bifurcated die-lever 9, the bed 35 of the die being pivotally attached to the block by a pin 36, and the opposed engaging edges of the bed and block formed with curved rocking faces or bearing faces 37 and 38. By 50 this construction the face of the die will engage the board end evenly although such end be slightly out of square or has a slanting face, and will consequently effect a perfect imprint.

55 The spring 16 which has one end secured to the pin 17 is attached at its other end to a tongue portion 39 of an extended curved portion 37' which latter is made integral with the die bed and is formed with shoulder portions 38' adapted to engage the die-lever arms. This arrangement in connection with the pivot 14 which secures the die to the die-lever operates to provide clearance for the lumber after the imprint has 60 been effected, as the die will yield before

the advancing board end by reason of said pivot 14 and spring 16 until the die is swung completely clear from the board end by engagement of the concave face 21 with the 70 roller 31.

I have shown the casing supported by a bracket 40, but the method of support will necessarily vary to adapt the device to different types of machines. For convenience of access to the interior of the casing there 75 is provided a hinged closure 41.

Having described my invention, its construction, operation, and utility, I claim:—

1. A device of the character described, consisting of a pivotally supported actuating-lever adapted to be engaged and operated by a moving object, a die-lever pivotally supported by the actuating-lever, means for imparting impact force to the die-lever, a latch member adapted to retain the die-lever in raised position, and retracting means for the actuating-lever.

2. A device of the character described, consisting of a pivotally supported actuating-lever adapted to be operated by a moving object, a die supporting lever mounted on the actuating lever, a spring connected to the latter lever for imparting impact force thereto, a pivoted latch-member adapted to engage the die supporting lever to retain 95 the same in raised position, a detent adapted to engage the latch-member, and spring means for retracting the actuating-lever into initial engagement with said moving object.

3. A device of the character described, 100 consisting of a pivotally supported actuating-lever adapted to be engaged and operated by a moving object, a die supporting lever pivotally supported by the actuating-lever and disposed at one side thereof, the 105 pivoted portion of the die supporting lever being provided with a fixed member engaging surface and a catch, a pivoted latch-member having a catch adapted to engage said first mentioned catch to retain the die 110 supporting lever in raised position, a pivoted detent adapted to engage said latch-member, a fixed member adapted to engage said engaging surface, and a spring connected to said die supporting lever adapted 115 to retract said actuating-lever and to impart impact force to said die-lever.

4. The combination in a number marker of a pivoted die lever, mechanism for swinging the lever and means for retaining said 120 lever in raised position, a die block pivoted on the lever and a die pivoted on the block with its pivotal axis at right angles to the pivotal axis of the block and having a limited swinging movement on the block to 125 adapt said die to irregularities, the opposed engaging portions of the die and block having curved bearing faces, and a spring connection between the die and lever.

5. The combination with a pivoted actu- 130

ating lever in the path of movement of an object, of a die carrying lever pivoted in the actuating lever, means for imparting impact force to the die lever, means for retaining the die lever in raised position, and means for retracting the actuating lever.

5. The combination with a pivoted actuating lever adapted to be operated by a moving board, of a die lever pivoted in the actu-

ating lever and means for imparting impact force to the die lever, a die block pivoted in the die lever and a die flexibly pivoted in the block to adjust itself to irregularities in the board, means for retaining the die lever in raised position, and means for retracting 15 the actuating lever.

In testimony whereof, I affix my signature.
EUGENE F. MITCHELL.
